DESIGN FOR A COOKING STOVE

Bertrand N. Trombley, Oak Park, Mich., assignor
to The Murray Corporation of America, Detroit,
Mich., a corporation of Delaware

Application March 21, 1944, Serial No. 112,981

Term of patent 14 years

(Cl. D81—4)

To all whom it may concern:

Be it known that I, Bertrand N. Trombley, a citizen of the United States, residing in Oak Park, in the county of Oakland, State of Michigan, have invented a new, original, and ornamental Design for a Cooking Stove, of which the following is a specification, reference being had to the accompanying drawing, forming a part thereof, wherein:

The figure is a perspective view of a cooking

stove showing my new design in which the right-hand side is substantially like the side shown.

The characterizing features of the cooking stove disclosed reside in the top portions having the configurations shown in full lines.

What I claim is:

The ornamental design for a cooking stove, substantially as shown and described.

BERTRAND N. TROMBLEY.
